UNITED STATES PATENT OFFICE

BONNIE E. VAN ALSTINE, OF SAN FRANCISCO, CALIFORNIA

COPY AND BOOK HOLDER

Application filed December 8, 1930. Serial No. 500,896.

- The present invention relates to improvements in copy and book holders, and it consists in the combinations, constructions and arrangement of parts hereinafter described.
- 5 The device illustrated and claimed in the present application is a continuation in part of my co-pending applications Serial Numbers 380,163 and 447,286 filed July 22, 1929, and April 25, 1930, respectively.
- 10 More particularly it is proposed to incorporate in the present application the securing means disclosed in my former applications which are used in combination with a copy holder for securely holding a sidewise-opening book or the like in the holder in such a manner that the reading pages of the book are always firmly held in place, irrespective of the size of the book or the degree to which it is opened. The securing means are so arranged that all parts of the book are firmly supported at any degree of book opening.
- 15 This application further includes means for supporting the uppermost edges of an open book so as to keep them from sagging.
- 20 25 My invention is illustrated in the accompanying drawings forming a part of this application, in which:
- Figure 1 is a side view of my copy holder with a book secured thereto,
- 30 Figure 2 is a front elevation of the device,
- Figure 3 is an inverted plan view taken along line 3—3 of Figure 1,
- Figure 4 is a fragmentary side view of a portion of the device,
- 35 Figures 5 and 6 illustrate modifications of means for raising the sections of an open book into the same plane, these means being shown in side elevation,
- 40 Figure 7 is a partial plan view of a modified portion of the device, and
- Figure 8 is a vertical section on line 8—8 of Figure 7.
- While I have shown only the preferred forms of my invention, it is understood that 45 various changes or modifications may be made within the scope of the appended claims without departing from the spirit of the invention.
- In its preferred form my copy and book holder comprises a base 1 having a copy holding element or frame 2 swingably secured
- thereto as at 3, and braces 4 supporting the latter relative to the former at any desired angle. The braces 4 are pivoted to the back of the copy holder at 5, and are adapted for engagement with sockets 6 formed in the sides 55 7 and 8 of the base. Figure 1 illustrates one of the braces as engaging with the sockets on the side 7, and a similar brace is provided on the opposite side of the copy holder.
- The braces 4 are movable into parallel relation with the back of the copy holder frame and are securable thereto by spring clips 9. An additional spring clip 10 is provided as clearly shown in Figure 1, and is adapted to overlie the edge 11 of the base so as to firmly 60 clamp the copy holder in folded position when the copy holder is swung so as to abut against the base. It should be understood that the braces 4 are first placed in the clips 9 before the copy holding frame is lowered to the 65 base 1.
- The upper edge of the copy holding frame has a supporting member 12' extending rearwardly therefrom, and the same is provided with a swingable U-shaped strip of 70 metal 13'. The U-member may be moved into a vertical position and be made to serve as a handle for carrying the entire device.
- The parts thus far described form no part 75 of the present invention except insofar as they cooperate with the parts now to be described.
- The copy holding frame may be of any suitable shape, and in the present embodiment I have shown a rectangular shaped plate 12 having a shelf 13 extending therefrom and adapted to support a book 14 thereon in reading position. The lower edge of the book may rest on the shelf, and I provide detachable 80 means for holding the book in its proper position for copying. The latter means include two members 15 and 16 pivoted to the supporting member 12' and the shelf 13 respectively in the manner shown in the drawings, the upper member being formed with a series 85 of perforations 17 and the lower member with a plurality of serrations 18. These members are pivotally attached to the copy holding frame, and may be swung into an out-of-the-way position when it is so desired.
- 100

In Figures 1 and 2, I show a rod 19, preferably square in cross-section and having an arc-shaped end 20' adapted to be introduced into any one of the perforations in the member 15 so as to extend along the hinged section that is presented between the two sections of the book. The arc-shaped end 20' cooperates with the member 15 for providing a hinge. The lower portion of the rod is adapted for engagement by the serrations 18, and this clamps the open book to the supporting frame. When the bar is thus manually engaged, it may be swung laterally in order to follow the hinged section of the book as the same shifts with the turning of the leaves. As the rod 19 is thus shifted, it is moved toward and away from the plate 12, and I have therefore provided a cut-away portion 14' in the shelf 13. This also permits the serrations 18 adjacent to the plate 12 to be utilized. It is also apparent that the rod may be adjusted with respect to the plate 12 so as to accommodate various thicknesses of books.

The rod 19 has transversely-extending members 20 and 21 adjustably secured thereon by friction springs 20'' and set-screws 100, and these members bear against the pages of the book for keeping them in reading position. These members are preferably square in cross-section. The member 21 is flanged at 22 and adapted to engage the lower edges of the uppermost pages of the book and thus prevent them from sagging.

The rod 19 is also provided with a line indicator 23, the latter being frictionally held in place by means of a spring 23' and adjustable over the pages of the book so as to indicate the particular line that is being copied.

The line indicator is preferably flat so as to freely slide over the pages of the book. The lines of printed matter are held even under the line indicator by the flange 22 and the shifting of the members 15 and 16, and by means hereinafter described adapted for lifting either of the book sections so as to raise the exposed pages into contact with the transverse members and the line indicator. The members 15 and 16 are free to swing on their respective pivots so as to allow the rod 19 to twist slightly and move the line indicator into alignment with the lines of printed matter.

In Figures 7 and 8 I show a slight modification for securing the upper end of the rod 19 to the supporting frame, and the same consists of a pivoted bar 24 which is slotted at 25 for receiving a follower 26, the latter being held in adjusted position by a wing nut 27 and a bolt 28. The follower 26 carries a clamp 29 to which a bifurcated member 30 is swiveled, and the rod 19 is pivoted to the member 30 with freedom of swinging motion. The rod 19 may be adjusted toward or

away from the plate 12 in an obvious manner.

When a book is opened at a point other than at or near the center, the portions of the members 20 and 21 overlying the thicker section will bear against those pages, and the lines of print on this section will be properly aligned with the line indicator. In order that the lines of the other section may be presented in correct alignment with the indicator, it is necessary that the latter section be elevated until the exposed page thereof is also brought to bear against the transverse members and indicator.

I have provided several methods of obtaining this end, and I will now set them forth.

The preferred method of accomplishing this is to provide leaf springs 31 and 32 which are anchored to the plate 12 at 34' and extend along the parallel edges 32' and 33. These springs are made from relatively thin material and are fitted into recesses in the plate 12 and are readily flexed into operative position. The springs are slidably held in place near their upper ends by guides 34, and serve as trimmings for the board when they are not in use.

After the springs have been flexed and the sections of the book properly adjusted, the integral rearwardly-extending pins 35 are placed in perforations or sockets 36 formed along the edges 32' and 33. These sockets are exposed one at a time as the uppermost ends of the springs are moved downwardly, and these sockets extend at an angle with respect to the plane of the plate 12. The pins 35 project from the springs at a corresponding angle, and this construction prevents the pins from becoming accidentally disengaged from the sockets. Ears 37 are preferably formed integral with the springs 31 and 32, and may be grasped by the operator for facilitating the adjustment of the book sections.

For this purpose I may also provide strips of material 38 which are attached to the copy holding frame so as to lie in parallel relation with the edges 32' and 33. It should be understood that two strips are provided which are substituted for the springs 31 and 32. Each strip of material has a section 39 swingably secured thereto at 40, and the section is provided with a hinge 41 at an intermediate portion. The strips 38 are provided with a plurality of steps 42 with which the extreme end 43 may be engaged for raising the hinge 41 to a desired height, whereby the section of the overlying book is raised accordingly.

A further modification is shown in Figure 6 for raising the thinner section of the book. Levers 43' are pivoted to the frame 12 at 44, and when one section is thinner than the other, one of the levers is operated so as to project from the frame and to raise the thin-

ner section into contact with the overlying transverse members and line indicator.

Although I have illustrated only the flexible leaf springs in combination with the holding rod 19, it is of course understood that the modifications disclosed in Figures 5 and 6 may be readily used to fulfill the requirements.

I claim:

10 1. In a copy and book holder, a frame for supporting a sidewise-opening book thereon in reading position, a rod adapted for placing over the book hinge, and a transverse member slidable on the rod and having a depending flange for supporting the uppermost leaves of the book and preventing them from sagging.

2. In a copy and book holder, a frame for supporting a book in reading position, a 20 perforated member pivoted to one end of the frame and a serrated member pivoted to the opposite end, and a bar having a bent end adapted for introduction into any one of the perforations and forming a hinge with the 25 perforated member so as to dispose the bar over the hinge section of the book, the other end of the bar being engageable by the serrated member for clamping the book in place.

3. In a copy and book holder, a frame for 30 supporting a book thereon in open position, a slotted member secured to one end of the frame, a follower adjustably attached to the slotted member, a bar pivoted to the follower so as to overlie the hinge section of the book, 35 and a serrated member pivoted to the opposite end of the frame for engaging with the bar and clamping the book in place.

4. In a copy and book holder, a frame for supporting a book thereon in reading position, 40 means extending along the hinge section of the book and including laterally projecting arms, a line indicator carried by the hinge-engaging means, and means for raising and adjusting either section of the book into contact with the arms and the line indicator.

5. In a copy and book holder, a frame for supporting a book in reading position and having a series of perforations arranged 50 along the opposite sides thereof, leaf springs extending over the perforations and having one of their ends anchored to the frame, and projections carried by the free ends of the springs adapted for introduction into the 55 perforations for flexing the springs and raising the sections of the book into the same plane.

6. In a copy and book holder, a substantially rectangular-shaped frame for supporting a book in reading position, leaf springs anchored to the frame and extending along the opposite sides thereof, and means for flexing the springs and holding them in flexed position whereby the sections of the book 65 may be raised into the same plane, said

springs when in inoperative position providing a trimming for the frame.

7. In a copy and book holder, a frame for supporting a sidewise-opening book thereon in reading position, a rod adapted for placing over the book hinge, a transverse member slidable on the rod and having a depending flange for supporting the uppermost leaves of the book and preventing them from sagging, and a line indicator adjustable along the rod.

8. In a copy and book holder, a substantially rectangular-shaped frame adapted for supporting a book in reading position, leaf springs anchored to the frame and extending along the opposite sides thereof, finger-grasping ears projecting laterally from the leaf springs and clearing the frame, said springs being flexible for raising the overlying book sections, and means for holding the springs in flexed position.
